UNITED STATES PATENT OFFICE.

LAWRENCE B. GRAY, OF BOSTON, MASSACHUSETTS.

SOUND-MUFFLING ATTACHMENT FOR TELEPHONIC APPARATUS.

1,177,617.

Specification of Letters Patent.

Patented Apr. 4, 1916.

Application filed February 25, 1915. Serial No. 10,489.

To all whom it may concern:

Be it known that I, LAWRENCE B. GRAY, a citizen of the United States, and resident of Boston, in the county of Suffolk and State 5 of Massachusetts, have invented certain new and useful Improvements in Sound-Muffling Attachments for Telephonic Apparatus, of which the following is a specification.

This invention relates to sound muffling 10 or deadening attachments either for telephone transmitters, to enable the user to speak into the transmitter without being easily overheard by people nearby, or for telephone receivers to exclude external 15 sounds from the ear of the user of a receiver.

The invention consists in the improvements hereinafter described and claimed, having for their object the production of an 20 effective muffling attachment adapted to be quickly applied to and removed from a telephonic apparatus part or member, and also adapted, when embodied in a transmitter attachment, to be supported by both the body and the mouthpiece of the transmitter.

25 Of the accompanying drawings,—Figure 1 represents an end view of a transmitter attachment embodying my invention; Fig. 2 represents a section on line 2—2 of Fig. 1, and a side view of a transmitter to which the 30 attachment is operatively applied; Fig. 3 represents a fragmentary section on line 3—3 of Fig. 2; Fig. 4 represents an end view of a receiver attachment embodying the invention; Fig. 5 represents a section on line 35 5—5 of Fig. 4.

The same reference characters indicate the same or similar parts in all the views.

In Figs. 1, 2 and 3, 12 represents a tubular casing or shell which is contracted at one 40 end and there provided with a mouthpiece 13. The opposite end of the casing is provided with a socket formed to receive the body 14 of a telephone transmitter, said socket including a rigid annular portion 15 and a rigid end portion 16. The socket also 45 includes a compressible annular inner portion 15^a backed by the rigid portion 15 and adapted to closely hug the periphery of the transmitter body. The inner portion 15^a 50 and its projections may be formed from a strip of relatively thick felt or other compressible material which has transverse thickened portions or ridges extending across one of its sides forming projections. 55 15^b. Said projections are so arranged that they are under considerable radial compres-

sion when applied to the transmitter, so that the attachment is engaged with the transmitter by friction.

The arrangement of the strip 15^a and projections 15^b is preferably such that the projections are the only parts of the strip that are compressed by the body 14, as indicated by Fig. 3, so that the attachment may be applied and removed without undue frictional resistance. The socket also includes an annular facing layer 16^a preferably of felt, backed by the rigid end portion 16 and formed to bear on the face of the transmitter and prevent the passage of sound vibrations. The layer 16^a is preferably extended inwardly as shown, so that it covers the face of the transmitter and closely hugs the base of the usual mouthpiece 18, the inner margin of the layer 16^a being provided 75 with radial slits 16^b, which adapt the layer to pass freely over the larger end of the mouthpiece 18. The rigid end portion 16 forms an abutment or stop which prevents endwise displacement of the compressible 80 annular portion 15^a by the pressure exerted upon it in applying it to the perimeter of the transmitter so that said compressible portion yields only in a radial direction, and is therefore caused to act as a chuck firmly 85 grasping the transmitter.

19 represents an annular inner wall which is joined to the socket end 16, and partially subdivides the interior of the casing into an inner air chamber 20 containing the mouthpiece 18, and an outer air chamber 21, which extends to the contracted end of the casing 90 12.

Joined to the wall 19 is an annular head 23, which forms the inner end of the inner air chamber 20. Joined to the inner margin of the head 23 is a tapering tubular sound conducting member 24, which is formed to enter the outer end of the tapering mouthpiece 18. The member or conductor 24 is in alignment with the casing mouthpiece 13, and its functions are to conduct sound waves into the mouthpiece 18, and to aid in detachably engaging the attachment with the transmitter, the attachment being supported partly by the body and partly by the mouthpiece of the transmitter, and being readily applicable and removable.

25 represents a tapering tubular extension of the mouthpiece 13, projecting into the contracted end of the casing 12, and

serving to conduct sound waves toward the transmitter mouthpiece. The extension 25 is separated from the head 23 by an air space 27, which communicates with the outer 5 air chamber 21. Said air space is partly obstructed by annular baffle rings 28, 29 of felt or other sound absorbing material, said rings being preferably slotted. The object of said air space and baffle rings is to break 10 up and absorb sound waves and thus increase the muffling efficiency of the attachment. To further increase said efficiency, I preferably provide the head 23 with an annular flange 30, which partially subdivides 15 the outer air chamber 21.

The rigid parts of the attachment may be of a suitable metal such as aluminum or papier-mâché or other moldable material.

I have demonstrated by practical tests 20 that the interruption of the inner wall of the outer air chamber 21 by the space 27 containing the sound absorbing baffle rings, renders the attachment more efficient as a sound muffler than would be the case if the extension 25 and head 23 were brought together to form a continuous or uninterrupted sound conducting passage.

The tapering conductor 24 forming as described a part of the sound conducting passage through the attachment and a means 30 for engaging the mouthpiece 18 to cause the latter to aid in supporting the attachment, also forms a part of the wall of the inner air chamber 20.

35 The socket portion of the above-described attachment may be utilized as a part of an attachment for the ear piece of a telephone receiver 35, as shown by the modification illustrated by Figs. 4 and 5, the attachment 40 being composed of an annular body 36 of wood, papier-mâché, hard rubber, metal or other suitable material. Said body has at one end, an annular ear piece 37 formed to surround the external ear of the user of the

45 receiver, and bear closely on the hair or the side of the head around the ear, and thus muffle or shut out external sounds. The opposite end of the body has a socket which includes a rigid annular portion 38, and an 50 inner annular portion 38^a of compressible material such as felt, backed by the rigid outer portion, said inner portion being provided with transverse ridges or projections 38^b, the portion 38^a and its projections being

55 formed and applied like the above-mentioned portion 45^a and projections 15^b. The projections 38^b are adapted to closely hug and be compressed radially by the periphery of the receiver head. The socket also includes a rigid end portion 39, preferably of the stepped form shown by Fig. 5, and a stepped facing layer backed by the rigid portion 39 and adapted to bear on the outer end of the receiver head. Said facing layer 60 is preferably composed of two felt rings 39^a,

these rings forming steps which are compressible by the usual stepped end face surrounding the conducting passage communicating with the diaphragm of the receiver. The rigid end portion 39 acts as a stop or abutment preventing endwise displacement of the compressible portion 38^a. 70

The attachment is adapted to be quickly applied to and removed from the receiver, and constitutes an effective sound-muffling ear piece extension thereof. 75

The compressible projections on the cylindrical socket portion are adapted to fit transmitters or receivers of different sizes, without marring or scratching the same. 80

I claim:

1. A muffling attachment comprising a tubular casing having a mouthpiece at one end, a socket at the opposite end adapted to detachably engage the body of a telephone 85 transmitter, and an intermediate sound-conducting member rigidly supported in the casing and formed to enter and detachably engage the tapering mouthpiece of the transmitter. 90

2. A muffling attachment comprising a tubular casing having a mouthpiece at one end, a socket at the opposite end adapted to detachably engage the body of a telephone transmitter, and a tubular inner wall extending into the casing from said socket and provided at its inner end with an annular head and with a tapering tubular sound-conductor projecting from said head and formed to enter the tapering mouthpiece of the transmitter, said inner wall subdividing a portion of the casing into an inner air chamber formed to surround the transmitter mouthpiece and closed at one end by said head, and an outer air chamber extending to the mouthpiece end of the casing. 100 105

3. A muffling attachment comprising a tubular casing having a mouthpiece at one end, a socket at the opposite end adapted to detachably engage the body of a telephone transmitter, a tubular inner wall extending into the casing from said socket and provided at its inner end with a tapering tubular sound conductor formed to enter the transmitter mouthpiece, and a tubular mouthpiece extension projecting inwardly from the casing mouthpiece, said inner wall and mouthpiece extension being separated from the casing wall by an air chamber. 110 115

4. A muffling attachment comprising a tubular casing having a mouthpiece at one end, a socket at the opposite end adapted to detachably engage the body of a telephone transmitter, a tubular inner wall extending into the casing from said socket and provided at its inner end with an annular head having means for engaging the transmitter mouthpiece, a tubular mouthpiece extension projecting inwardly from the casing mouthpiece, said inner wall and mouthpiece extension 120 125 130

sion being separated from the casing wall by an air chamber, said extension being separated from said annular head by an air space communicating with said air chamber, and 5 non-resonant annular baffle rings of sound-absorbing material, partially obstructing said space and attached to the said mouthpiece extension and head.

5. A muffling attachment comprising a 10 tubular casing having a mouthpiece at one end, a socket at the opposite end adapted to detachably engage the body of a telephone transmitter, and a tubular inner wall extending into the casing from said socket 15 and provided at its inner end with an annular head and with a tapering tubular sound-conductor projecting from said head and formed to enter the tapering mouthpiece of the transmitter, said inner wall subdividing 20 a portion of the casing into an inner air chamber formed to surround the transmitter mouthpiece and closed at one end by said head, and an outer air chamber extending to the mouthpiece end of the casing, said head 25 being provided with an outer flange part.

6. A muffling attachment comprising a 10 tubular casing having a mouthpiece at one end, a socket at the opposite end adapted to detachably engage the body of a telephone transmitter, and intermediate means within 15 the casing for detachably engaging the mouthpiece of the transmitter, said socket being composed of a cylindrical portion provided with an inner layer of compressible

material adapted to be compressed by the 35 periphery of the transmitter body, and an inner end portion adapted to bear on the outer face of said body and having a facing layer of compressible material formed to bear on the face of the transmitter body, 40 said facing layer being extended inwardly to form a flexible annular flap adapted to pass over the transmitter mouthpiece.

7. A sound-muffling attachment comprising 45 an annular sound-conducting body having at one end an annular sound-conducting member and at the other end a socket formed for detachable application to a telephone part, and including a rigid annular outer 50 portion having a relatively wide inner surface, and a compressible annular inner portion backed by the rigid outer portion and having spaced compressible projections adapted to be radially compressed by and to closely hug said telephone part, said socket 55 also including a rigid end portion constituting a stop which confines the said compressible annular portion against endwise displacement and is provided with a compressible facing adapted to bear on an end face 60 of said telephone part.

In testimony whereof I have affixed my signature, in presence of two witnesses.

Correction in Letters Patent No. 1,177,617.

It is hereby certified that in Letters Patent No. 1,177,617, granted April 4, 1916 upon the application of Lawrence B. Gray, of Boston, Massachusetts, for an improvement in "Sound-Muffling Attachments for Telephonic Apparatus," an error appears in the printed specification requiring correction as follows: Page 3, claim 5, after line 25 insert the words and syllables *tially subdividing the outer air chamber.*; and that the said Letters Patent should be read with this correction therein that the same may conform to the record of the case in the Patent Office.

Signed and sealed this 9th day of May, A. D., 1916.
